(57) **CLAIM**

The ornamental design for an auxiliary vehicle hood as shown and described.

DESCRIPTION

FIG. 1 is a front view of an auxiliary vehicle hood showing my new design;

FIG. 2 is a rear view of the auxiliary vehicle hood;

FIG. 3 is a right side view of the auxiliary vehicle hood;

FIG. 4 is a left side view of the auxiliary vehicle hood;

FIG. 5 is a top view of the auxiliary vehicle hood;

FIG. 6 is a bottom view of the auxiliary vehicle hood;

FIG. 7 is a top front side perspective view of the auxiliary vehicle hood; and,

FIG. 8 is a top front side perspective view of the auxiliary vehicle hood in use.

The broken lines in FIG. 2 are illustrative of portions of the article forming no part of the claimed design. The broken lines in FIG. 8 are illustrative of environmental structure forming no part of the claimed design.
